UNITED STATES PATENT OFFICE.

AMERICUS MERIDA BARNETT, OF ELKTON, KENTUCKY, ASSIGNOR OF ONE-HALF TO JOHN B. WRIGHT, OF SAME PLACE.

SHEARS.

SPECIFICATION forming part of Letters Patent No. 337,917, dated March 16, 1886.

Application filed December 17, 1885. Serial No. 185,941. (No model.)

To all whom it may concern:

Be it known that I, AMERICUS MERIDA BARNETT, a citizen of the United States, residing at Elkton, in the county of Todd and State of Kentucky, have invented a new and useful Improvement in Scissors, of which the following is a specification, reference being had to the accompanying drawings.

My invention relates to improvements in scissors; and the novelty consists of the peculiar construction, combination, and adaptation of the various parts, substantially as herein-after fully set forth, and specifically pointed out in the claims.

15 The primary object of my invention is to provide a pair of scissors with detachable and reversible handles to adapt either end of the blades for use, both ends of the said cutting-blades being sharpened or provided with 20 cutting-edges, whereby when one end of the cutting-blades becomes dulled, through use or otherwise, the handles or thumb guards can be detached and reversed, so as to adapt the other sharpened edges of the reverse ends of the 25 blades for use.

A further object of my invention is to provide novel means for securing the handles to the blades in a secure and firm manner, and to 30 combine simplicity, strength, and durability of construction with thorough effectiveness of operation and cheapness of manufacture.

In the accompanying drawings, Figure 1 is a perspective view of a scissors embodying my invention. Fig. 2 is a like view with the handles reversed. Fig. 3 is a cross-sectional view 35 on the line $x-x$ of Fig. 1. Fig. 4 is a detail view of one of the blades. Fig. 5 is a detail view of the pivoted blades with the handles removed. Fig. 6 is a detail view of one of the 40 detachable handles. Fig. 7 is a detail view of one of the handles with a pivoted securing-latch.

Referring to the drawings, in which like letters of reference denote corresponding parts in 45 all the figures, A B designate the cutting-blades, which are pivoted together near one end, so as to provide a pair of cutting-blades at each end, which are of unequal lengths—that is to say, the pair of blades a at one end

are considerably longer than the blades b at 50 the opposite end. Each of the blades of each pair are tapered or pointed toward their extreme ends, as shown, and they are provided on opposite side edges with sharpened cutting-edges, to adapt either side edge to be used for 55 cutting.

Each of the blades A B is provided with two upwardly-projecting lugs, c c', which are arranged on opposite sides of the pivot b' of said blades A B, and extend in the direction 60 of the longitudinal axis of the blades. These lugs are tapered or pointed toward their ends, and on their vertical faces at their bases they are provided with curved or inclined grooves c'', for the reception of the spring-arms d of the 65 detachable handles D. These handles D each comprise a shank, d', a thumb-guard, d'', of the ordinary or well-known form, and the spaced-apart spring-arms d, all of which are preferably formed of one piece of metal for 70 strength and durability. The inner edges of the arms d are curved or inclined to correspond to the shapes of the grooves in the lugs c c', and when it is desired to fit one of the 75 handles D to one of the lugs c or c' the ends of the spring-arms are fitted against one of the pointed ends of said lugs within the groove therein, and it is then forced inwardly, the spring-arms yielding to the inclination of the lugs and closely fitting and encompassing the 80 same within the grooves thereof.

If desired, the handles may have finger guards or lugs cast or formed thereon, to prevent the fingers of the user from being cut by 85 the blades.

The pivot b' of the cutting-blades A B may be the ordinary pin, which is headed down on the outer faces of the blades at the ends, or it may comprise a pin having two spring-arms and a fastening wedge or key at one end, this 90 latter device being particularly useful and desirable when the blades are to be separated for purpose of sharpening them.

In Fig. 6 I have shown a pivoted latch, E, for locking the handle to the lug c or c' of the 95 blades, to prevent the accidental detachment of the handle from the cutting-blades and provide a very firm and secure connection be-

tween the parts; but in lieu of this latch a spring-catch may be provided for connecting the parts.

The shorter blades, *b*, are especially designed 5 for cutting button-holes; but if it is found desirable the blades *a b* may be formed of equal length.

It will be seen from the foregoing description, taken in connection with the drawings, 10 that when one of the pairs of blades *a b* have become dulled through wear and usage the handles *D* can be readily detached from the lugs of the sharpened blades and secured or fitted upon the lugs of the dulled blades, the 15 blades being reversed so as to bring the sharpened blades into play.

The handles can be easily and readily detached and reversed, and the blades very 20 readily sharpened.

25 The device is very cheap and strong, is simple in its construction, and thoroughly effective for the purposes designed.

Having thus described my invention, what I claim as new, and desire to secure by Letters Patent, is—

25

1. In a scissors, the combination, with the pivoted blades having the lugs *c c*, provided with grooved faces, of the detachable and reversible handles *D*, having the spring-arms *d*, to closely fit the lugs, substantially as de- 30 scribed.

2. The combination of the pivoted blades having the lugs, the detachable and reversible handles having the spring-arms, and a pivoted latch carried by the handles, substantially as 35 described.

In testimony that I claim the foregoing as my own I have hereto affixed my signature in presence of two witnesses.

AMERICUS MERIDA BARNETT.
